UNITED STATES PATENT OFFICE.

JOSEPH SLEPIAN, OF WILKINSBURG, PENNSYLVANIA, ASSIGNOR TO WESTINGHOUSE ELECTRIC & MANUFACTURING COMPANY, A CORPORATION OF PENNSYLVANIA.

OSCILLATION GENERATOR SYSTEM.

Application filed April 21, 1921. Serial No. 463,210.

To all whom it may concern:

Be it known that I, JOSEPH SLEPIAN, a citizen of the United States, and a resident of Wilkinsburg, in the county of Allegheny 5 and State of Pennsylvania, have invented a new and useful Improvement in Oscillation Generator Systems, of which the following is a specification.

My invention relates to thermionic devices 10 and particularly to externally controlled thermionic devices which may be employed as oscillators in oscillation-generator systems.

The object of my invention is to provide 15 an electrical system whereby the negative charges which have hitherto formed on the inner walls of thermionic devices employing an external control electrode are caused to be formed upon the external electrode itself 20 where the rate of leakage of the charge therefrom may be selectively controlled.

In the normal operation of three-electrode 25 vacuum tubes employing an external control electrode, which is so disposed that the field of force therefrom is substantially parallel to the space-current path between the electrodes within the vacuum tubes, it has been found that the inner surface of the vacuum tube acquires a mean negative charge.

Furthermore, it has been found that, in 30 the operation of such devices as detectors, amplifiers, or oscillators, a close adjustment of the rate of leakage of the charge from the inner walls of the vacuum tube is required for the most efficient operation thereof. The rate of leakage of the charge has 35 been found, experimentally, to depend, among other things, upon the residual gas within the tube, the filament current and the plate voltage.

It is evident that the rate of leakage of the charge from the inner surface of the walls of such tubes is not subject to close control in the manufacture thereof, so that the adjustment of the leakage must be effected by 45 varying the filament temperature and plate voltage. The disadvantage, however, of so adjusting the leakage, is that there is a tendency for the working adjustment of the tube 50 to become critical in value.

According to my invention, I provide means whereby the negative charge is caused to form on the external control electrode rather than on the inner walls of the tube, 55 and, in addition, means are provided for

selectively controlling the rate of leakage of the negative charge.

The negative charge is prevented from forming on the inner surface of the tube by shunting the control electrode and the filament with an electron valve which is so connected that the grid is prevented from assuming positive potentials with respect to the filament, the electrons being attracted to the inner surface of the walls of the tube 60 only when the control electrode is positive with respect to the filament.

A condenser is inserted in series with the external control electrode or grid circuit to admit of the electrode acquiring and maintaining a mean negative potential during the operation of the tube as an oscillator. The rate of leakage of the charge so formed on the control electrode is varied by a grid leak which affords a path over which the 75 charges on the condenser and grid may pass to the filament.

Other objects, as well as details of construction, whereby my invention may be carried out, will be apparent from the following 80 description, taken in connection with the accompanying drawings and claims, wherein;

The single figure is a diagrammatic representation of circuits and apparatus embodying my invention.

Referring to the single figure, I show an evacuated electrode device 1 having suitably disposed therein a hot cathode 2 and an anode 3, and an external electrostatic control electrode 4. The control electrode 4 is 90 so disposed adjacent the exterior surface of the evacuated electric device 1 that the hot cathode 2 lies in a plane between the anode 3 and the control electrode 4. In the arrangement shown, the control electrode 4 is 95 so disposed that the field of force between the hot cathode 2 and the control electrode 4 is substantially parallel to the field of force between the hot cathode 2 and the anode 3, though I do not wish my invention to be 100 limited to such an arrangement of elements. The hot cathode 2 is energized by means of a source of energy 5.

A plate-filament circuit comprises a stop- 105 ping condenser 6, a portion 7 of the tuning coil 8 and a conductor 9. A grid-filament circuit comprises a condenser 11, a portion 12 of the tuning coil 8 and the conductor 9. The mutual coupling between the plate-filament circuit and the grid-filament circuit is 110

that existing between the portions 7 and 12 of the tuning coil 8. A single condenser 13, which is connected to points on the portions 7 and 12 of the tuning coil 8, may be employed to tune the grid-filament and plate-filament circuits simultaneously.

The plate-filament circuit is energized by means of a source of direct-current energy 14, which is connected in shunt relation to 10 the anode 3 and the hot cathode 2, through a conductor 15 and a reactor 16. The grid or control electrode 4 is prevented from assuming a positive potential with respect to the hot cathode 2 by means of a thermionic 15 valve 17 which comprises an anode 18 and a hot cathode 19. The anode 18 is connected to the control electrode 4 by means of a conductor 21. The hot cathode 19 is connected to the hot cathode 2 and is also energized by 20 the source of energy 5.

The rate of leakage of the charge from the grid 4 is controlled by means of a variable resistor 22 which, for purposes of illustration, has been shown as directly connecting 25 the grid 4 and the hot cathode 2, though it is equally effective when connected in any other manner that affords a path over which the condenser 11 may discharge. The resistance 22 and the tube 17 are in shunt to each 30 other and may also be regarded as in shunt to the conductor 9, inductor 12 and condenser 11, in series.

Having thus described the elements of the system embodying my invention, the operation thereof is as follows:

Assuming the grid leak 22 and the thermionic valve 17 removed from the system shown in the drawing, upon the supply of energy to the plate-filament circuit, the tube 40 functions as an oscillation generator. As hereinbefore stated, during the first assumption of a positive potential by the grid 4, large numbers of electrons are attracted to the inner surface of the walls of the tube 45 forming negative charges thereon. The potential variations of the grid 4 with respect to the filament 2 are, therefore, effected above and below some mean negative value which is determined by the negative charge 50 on the inner surface of the tube.

With the arrangement of circuits, as shown in the drawing, however, upon the tendency of grid 4 to assume a positive potential with respect to the filament 2, the electron valve 17 becomes effective as a short-circuit path. Thus, by preventing the grid 4 from assuming a positive potential, with respect to the filament 2, substantially no electrons are attracted to the inner surface of the walls of the tube.

In order to cause the grid 4 to assume a mean negative potential, such as is effected by the negative charge ordinarily formed on the inner walls of the tube 1, I have provided a condenser 11 in the grid-filament

circuit. The rate of leakage of the negative charge so formed may readily be controlled by means of the resistor 22.

The advantage of my invention resides in the provision of simple and efficient means 70 whereby the rate of leakage of the negative charges from tubes employing external control electrodes may be readily adjusted to such values as are necessary to effect efficient operation of the tubes as detectors, as amplifiers or as oscillators. 75

While I have shown my invention as applied to a particular arrangement of circuits, I do not wish to be limited thereby but I desire that only such restrictions shall be 80 placed upon my invention as are set forth in the appended claims.

I claim as my invention:

1. The combination with an evacuated electric device having a space-current path 85 therein, of electrostatic means for preventing the formation of a negative charge upon the inner surface of the walls thereof.

2. The combination with an evacuated electric device having a space-current path 90 therein and an external control electrode, of means for preventing the formation of positive charges upon said control electrode.

3. The combination with an evacuated electric device having a space-current path 95 therein and an external control electrode, of means for causing said external control electrode to assume a mean negative charge, and means for varying the value of said mean negative charge. 100

4. The combination with a vacuum-tube device having therein a cathode and an anode, of an external control electrode therefor, and a rectifying device connected in shunt to said cathode and said control electrode. 105

5. The combination with a vacuum-tube device having therein a cathode and an anode, of an external control electrode therefor, means including a rectifying device for causing said control electrode to assume a mean negative charge, and means for controlling the rate of leak of said charge. 110

6. An oscillation-generator system comprising an evacuated electric device having a space-current path therein, means for causing said evacuated electric device to function as an oscillation generator and means outside said space-current path for preventing the formation of negative charges on the inner surface of the wall of said evacuated electric device. 115

7. An oscillation-generator system comprising a vacuum-tube device having therein a hot cathode and an anode, an external-control electrode disposed adjacent the exterior surface of said vacuum-tube device, means for causing said vacuum-tube device to function as an oscillator, and a rectifying device connected in shunt to said hot cathode 120

125

130

and said control electrode whereby negative charges are prevented from forming on the inner surface of said vacuum-tube device.

8. An oscillation-generator system comprising a vacuum-tube device having a space-current path therein, electrodes individual to said space-current path, an external-control electrode disposed adjacent the exterior surface of said vacuum-tube device, means for 5 causing said tube to function as an oscillator, a thermionic valve connected in shunt to said external-control electrode and one of said electrodes for preventing the formation of negative charges on the inner surface of 10 said vacuum-tube device, means for causing the formation of a mean negative charge on the external electrode, and a resistor connected in shunt to said control electrode and one of said electrodes for controlling 15 the rate of leakage of said negative charge.

9. In an electrical system, the combination with an evacuated electric device having a filament and an anode therein and a control electrode disposed immediately adjacent the 25 external surface of said evacuated electric device, of a tuned plate-filament circuit including a coupling coil, a grid-filament circuit including a condenser and a coupling coil, said coupling coils being mutually inductive, 30 means for energizing said plate-filament circuit, and a resistor and a thermionic valve connected in a shunt circuit around a portion of said grid-filament circuit including said condenser, said thermionic valve being 35 so connected as to prevent the formation of positive charges upon said control electrode.

10. In an electrical system, the combination with an evacuated electric device having a hot filament and an anode therein, means 40 for producing an electron stream therebetween, and an external control electrode so disposed that the field of force therefrom is substantially parallel to said electron stream, of a tuned plate-filament circuit including a 45 coupling coil, a grid-filament circuit including a condenser and a coupling coil, said

coupling coils being mutually inductive, means for energizing said plate-filament circuit, and a resistor and a thermionic valve each connected in a respective shunt circuit 50 around a portion of said grid-filament circuit including said condenser, said thermionic valve being so connected as to prevent the formation of positive charges upon 55 said control electrode.

11. The combination with an electron tube having an enclosing vessel and means for establishing a space-current path therein, of an externally disposed control electrode, a control circuit including a condenser in series with said control electrode, and means for producing the effect of a grid leak in a shunt circuit around a portion of said control circuit, said portion including said condenser. 60

12. An electron tube comprising an enclosing vessel, a cathode and an anode constituting two internal electrodes therein, means including an externally disposed electrode for producing a controlling electrostatic 70 field, one of said internal electrodes being disposed between said external electrode and the other internal electrode, and means for substantially preventing said external electrode from accumulating a positive charge 75 with respect to said cathode.

13. In a vacuum-tube device, a container having internal electrodes and an external electrode, means cooperating with said electrodes for impressing a periodically alternating potential on said external electrode, whereby the potential of said external electrode tends to alternate, and means for maintaining said external electrode at a potential corresponding to the amplitude of one 80 sign only of said periodic potential, whereby the mean potential of said external electrode is given a predetermined sign.

In testimony whereof, I have hereunto subscribed my name this 14th day of April 85 1921.

JOSEPH SLEPIAN.
